UNITED STATES PATENT OFFICE.

CHARLES M. STEVENSON, OF CHICAGO, ILLINOIS, ASSIGNOR TO STEVENSON MFG. CO.,
OF BARTON, WISCONSIN, A CORPORATION OF WISCONSIN.

INCLOSURE, PEN, FENCE, AND THE LIKE.

1,352,392.

Specification of Letters Patent. Patented Sept. 7, 1920.

Application filed September 29, 1919. Serial No. 327,173.

To all whom it may concern:

Be it known that I, CHARLES M. STEVENSON, a citizen of the United States, and a resident of the city of Chicago, county of Cook, and State of Illinois, have invented certain new and useful Improvements in Inclosures, Pens, Fences, and the like, of which I do declare the following to be a full, clear, and exact description, reference being had 10 to the accompanying drawing, forming part of this specification.

This invention relates to inclosures, pens, fences and the like, and its principal object is to provide a simple and rigid structure, 15 such as inclosures, cattle pens, fences and the like, which is easily and quickly assembled and installed in place. Another object is to provide a device of this character capable of being constructed of stock materials, such as channel irons, ordinary castings, pipes and bolts and nuts, thus dispensing with the necessity of providing a 20 large number of patterns, gigs, dies and special machinery and tools for constructing 25 devices of this character. The invention consists in the several novel features herein-after fully set forth and claimed.

The invention is clearly illustrated in the accompanying drawing, in which—

30 Figure 1 is a side elevation of a fragment of an inclosure embodying a simple form of the present invention; Fig. 2 is a detail plan of a fragment thereof with a certain stanchion member partly broken away; Fig. 35 3 is a detail, fragmental, cross section taken on line 3—3 of Fig. 1; and, Fig. 4 is a detail vertical cross-section taken on line 4—4 of Fig. 1.

Referring to said drawing, which illustrates a simple embodiment of the invention, the reference character 5 designates a rail, and 6 a number of uprights or spindles, the upper ends of which are rigidly secured in the rail, and the lower ends of which may 45 be embedded in a concrete curb 7 formed on the floor of the pen or other structure, with which the inclosure is used. In its simplest form, the rail comprises two companion, webbed or channel iron bars 8, 8, placed side 50 by side, with their channels facing each other, to provide a rail of substantially square or rectangular cross section. The channel iron bars 8, are secured together at intervals by bolts and nuts 9 which connect 55 the vertical webs 10 of the bars. At the

places where the spindles 6 are secured to the rails, holes 11, of slightly less diameter than that of the spindles, are drilled in the lower flanges 12, and the edges of said holes are arranged to bite upon or impinge 60 against the sides of the spindles 6. In assembling the rails and spindles, the nuts are loosened, the upper ends of the spindles inserted through the holes 11 and pushed up against the lower sides of the flanges of the 65 rails, after which the nuts are tightened up on the bolts, thereby tightly clamping the edges of the holes 11 upon the spindles and producing a rigid and substantial connection 70 between the rail and spindle.

A structure built in accordance with the one herein described, lends itself particularly for use in connection with cattle stanchions, and I have illustrated one, which, as shown, 75 comprises two stanchion members 14 preferably constructed of pipes or other tubular members, flattened at the top and bottom, as at 15, 16. The upper and lower flanges 13, 12 of the rail 5 are slotted as at 17 to receive the upper flattened ends 15 of the 80 stanchion members and latches 18 are pivotally connected with said upper ends and arranged for engagement with a keeper 19 which is bolted to the rail midway between 85 the stanchion members. When engaged with the keeper 19, the latches hold the stanchion members in closed or locked position.

The lower flattened ends of the stanchion members are pivotally connected to a lower rail 20 which may be constructed in substantially the same manner as the upper rail 5 and clamped to adjacent spindles. Said lower rail 20 is slotted for the reception of the lower flattened ends of the stanchion members, and bolts and nuts 21 are 95 preferably employed for pivotally connecting said stanchion members to the lower rail. Obviously in certain situations the lower rail may extend the full length of the structure and the spindles may end in the 100 lower rail in the same manner as they end in the upper rail. In this case certain of the spindles, and especially the corner or end ones, project down below the lower rail and are embedded in the floor or ground 105 where the structure is used.

From the above it is apparent that a rigid, substantial and durable structure is obtained, which effectively resists hard usage. The joints between the rails and spin- 110

dles are tight, and in case any one becomes loose, it requires but a moment to tighten the nuts to clamp the rail on the spindles.

More or less variation of the exact de-
tails of construction is possible without de-
parting from the spirit of this invention;
I desire, therefore, not to limit myself to
the exact form of the construction shown
and described, but intend in the following
claims to point out all of the invention de-
scribed herein.

I claim as my invention:

1. In a structure of the class described,
a rail comprising two companion, webbed
bars arranged with their channels facing
each other and with their upper marginal
edges abutting against each other, there be-
ing opposing semi-circular holes in the
lower sides of said bars, spindles extending
through said holes, and bolts and nuts con-
necting said bars and clamping them upon
said spindles with the abutting upper edges
clamped together throughout.

2. In a structure of the class described,
a rail comprising two companion, channel
iron bars arranged with their channels fac-
ing each other and their upper marginal
edges abutting against each other, there be-
ing opposing semi-circular holes in the
lower flanges of said bars, spindles extend-
ing through said holes, and bolts and nuts

connecting said bars and clamping them
upon said spindles with their abutting up-
per edges clamped together throughout.

3. In a structure of the character de-
scribed, a rail comprising two companion,
channel iron bars, arranged with their chan-
nels facing each other, and their upper
marginal edges abutting against each other,
there being opposing, semi-circular holes in
the lower flanges of said bars, pipes of
larger diameter than said holes, extending
therethrough, and bolts and nuts connect-
ing said bars and clamping the edges of
said holes against said bars and clamping
the upper abutting edges of the bars to-
gether throughout.

4. In a structure of the character de-
scribed, a rail comprising two companion,
channel iron bars, arranged with their chan-
nels facing each other, and their upper mar-
ginal edges abutting against each other,
there being opposing, elongated rectangular
holes in the flanges of the bars, for the re-
ception of stanchion members, and semi-
circular holes in the lower flanges of said
bars, pipes of larger diameter than said
holes, extending therethrough, and bolts
and nuts connecting said bars and clamping
the edges of said holes against said bars.

CHARLES M. STEVENSON.
